UNITED STATES PATENT OFFICE

2,566,459

AWNNG HINGE

Frank Vernon McCoy, Springfield, Ohio, assignor
to The Springfield Tent & Awning Company,
Springfield, Ohio, a corporation of Ohio

Application April 26, 1950, Serial No. 158,253

7 Claims. (Cl. 160—81)

1

This invention relates to awnings. More particularly, it relates to a hinge which permits the folding of arms of the extending awning support. Still more particularly, it relates to a simplified form of fixture positionable in the straight portion of the awning supports, permitting folding of the support arms in back of one another when not in use.

Several types of awnings are in common use which consist of fabric or web having the upper end adapted for securing to the building structure over a window or the like and having the lower portion provided with appropriate supports to hold the lower portion in extended position.

The supports are generally rigid U-shaped members with the parallel arms adapted at their ends with suitable fastening means.

When awnings are removed from the building, storage of the awning is a problem because of the cumbersome nature of the U-shaped supports.

To overcome these difficulties said supports have been formed with threaded elbows connecting the bight or front arm with the side arms. While this makes disassembly possible, it has some drawbacks as rusting at the threaded portions and necessity for pipe fitting equipment to disassemble the unit.

Another type of collapsible unit has been in use which forms the bend of the U-shaped member as a hinge. This permits folding the arms in back of the bight, but the structures have lacked rigidity because they require ears on the ends of arms connected by pivots to opposite ends of link members.

With the foregoing conditions in mind, the present invention has as an object the provision of a highly simplified structure for the support member, overcoming the limitations and disadvantages of the prior devices.

It is an object of the present invention to provide an awning which has a foldable support member.

It is another object of the present invention to provide an awning which need not be disassembled for storage.

It is still another object of this invention to provide an awning which need only have the arms folded and the folded portion wrapped around with the attached awning to produce a relatively small roll ready for storage.

It is a still further object of the present invention to provide an awning whose support member is rigid when the arms are opened to extended position for attachment to a building.

It is another object of this invention to pro-

2

vide a hinge member for support bars which are adaptable to folding arms for any shape of support member and still maintain rigidity.

It is still another object of this invention to provide a hinge support member which can readily be withdrawn from the tubular or loop structure through which the awning is fixed to the support when the awning is to be removed for cleaning or repair.

A further object of this invention is to provide a hinge member for awning support wherein the enclosing shell limits the return movement of the arms creating rigidity in extended position.

Various other and more detailed objects and advantages will become apparent as the description of this invention proceeds.

More in detail, the invention comprises an awning support member of desired shape adapted at the ends to be secured to a building structure and which is formed from a plurality of separate members joined by means of rigid connector fixtures, each connector being adapted to receive a first member in an enclosed position and a second member in a position permitting the second member to be moved through a suitable angle for bringing the swinging arm in approximately back to back arrangement with the first member.

When utilizing a U-shaped support frame the rigid connector will be a straight member positioned adjacent the bend in the frame and one arm attached thereto will be free and movable through an angle of approximately 90 degrees. When the connector is not a straight member, it will at once be apparent that the swing angle may be more or less than 90 degrees.

The invention will be more fully understood from the following description in which for purposes of clearly describing this invention, the description will relate to a U-shaped support member and accompanying drawings wherein:

Figure 1 is a perspective view of an awning in place on a window frame, the lower portion of the awning being partially broken away to show the construction more clearly;

Figure 2 is a plan view of a support member in folded position;

Figure 3 is a plan view of another support member having the fixtures in different positions from those shown in Figure 2;

Figure 4 is a side elevational view of the connector or fixture as seen in Fig. 1;

Figure 5 is an inside elevational view of the fixture of Figs. 1 and 6; and

Figure 6 is an end view of the fixture.

3

Figure 7 is a view showing the frame in folded position.

Referring now to the drawings, the numeral 10 indicates the window frame of a building. An awning designated 11 is shown attached by suitable means, such as screws or turnbuckles, and the like, at its upper end to the top cross member 12 of the window frame or sash 10.

The lower portion of awning 11 is supported in extended position by the U-shaped frame 13, the inner ends of which are anchored to the vertical members 14 of window frame 10 by suitable brackets 15.

The U-shaped frame 13 as illustrated is made up of three members, side arms 16 and 17 and the front arm 18. Arm 18, as illustrated in Figure 2, is shown as provided with right angle bends at both ends of the front arm.

Reference to Figure 3 shows the side arms adapted with right angle bends and connected by a straight front arm, illustrating that there are many modifications which are entirely feasible.

Connecting front arm 18 with the side arm 16 is a rigid connector unit or fixture 20. Connector 20 may be a cast unit, preferably of non-rusting metal, or may be formed about a mandrel of suitably shaped sheet metal.

Fixture 20 is formed having an end portion 21 of a substantially closed tubular construction of any desired configuration, to match the configuration of any of the arms of the framework. Inasmuch as front arm 18 is illustrated as round, the illustration shows the substantially tubular wall as having a round configuration. The tubular portion, however, can be circular, rectangular or square, or other suitable cross sectional configuration.

The opposite end portion 22 of the fixture is formed U-shaped having straight sides 23 and 24 spaced apart a distance equal to the diameter of portion 21.

Connecting the straight sides is an integral back wall 25 of suitable configuration to permit unobstructed swing for the end of the connected arm member. The side opposite the back wall 25 is open for substantially the entire length of section 22.

Sections 21 and 22 are apertured at 26, 27, 28 and 29 to receive suitable securing means 30 for the members 16 and 18, such as rivets or bolts.

The preferred method of fabricating the fixture is to stamp a blank of desired configuration from a flat piece of sheet metal. The flat metal is then positioned in a press which transforms the flat blank into a U-shaped member and at the same time stresses the back wall portion 25 into a slightly arcuate configuration.

The parallel sides of the upper portion are then pressed by a separate die into tubular form. The apertures may be formed either as a part of the blank stamping operation or may be drilled later utilizing a jig to obtain accurate alignment.

While a preferred specific embodiment of the invention is hereinbefore set forth, it is to be clearly understood that the invention is susceptible to modification in order to adapt it to different usages and conditions and, accordingly, it is desired to comprehend such modifications within this invention as may fall within the scope of the appended claims.

I claim:

1. The method of forming a fixture for joining arms of an awning support rigid in extended position and foldable on one another when not

4

in use which comprises: punching from a flat sheet of metal a blank having one portion thereof of slightly greater width than another portion and simultaneously punching a pair of spaced apertures in each portion, forming the unit to U shape by punching with a die thereby bringing the apertures of each pair into axial alignment, forcing the edges of the portion of greatest width into close proximity to one another while supporting the unit internally with a member of predetermined external configuration, and positioning securing means in each of the pairs of apertures.

2. The method of forming a fixture for joining arms of an awning support rigid in extended position and foldable on one another when not in use which comprises: punching from a flat sheet of metal a blank having one portion thereof of slightly greater width than another portion and simultaneously punching a pair of spaced apertures in each portion, forming the unit to U shape by punching with a die thereby bringing the apertures of each pair into axial alignment, forcing the edges of the portion of greatest width into close proximity to one another while supporting the unit internally to produce a unit of substantially tubular cross sectional configuration, and positioning securing means in each of the pairs of apertures.

3. The method of forming a fixture for joining arms of an awning support rigid in extended position and foldable on one another when not in use which comprises: punching from a flat sheet of metal a blank having one portion thereof of slightly greater width than another portion, forming the unit to U shape by punching with a die, forcing the edges of the portion of greater width together while supporting the unit internally with a member of predetermined external configuration, drilling pairs of axially aligned apertures in both the tubular and U-shaped portions, and positioning securing means in each of the pairs of apertures.

4. In a fixture for securing together the adjacent end portions of a front arm and side arm of a U-shaped awning frame, the structure comprising a rigid shell having a first tubular portion having a longitudinal slot therein and a second U-shaped portion having the open end thereof of adjacent said slot, each said portion having arm securing means therein extending between opposing side walls, one said securing means enclosed by said shell being adapted to receive a said end of one said arm and the other said securing means being adapted to receive a said end of the other said arm in pivotal engagement whereby said other arm may be rotated toward said arm on said enclosed securing means to be positioned in back to back relationship therewith.

5. In a fixture for securing together the adjacent end portions of a front arm and side arm of a U-shaped awning frame, the structure comprising a rigid shell having a first tubular portion having a longitudinal slot therein and a second U-shaped portion having the open end thereof of adjacent said slot, said shell having spaced parallel bolts, one in each said portion and each extending between opposing side walls, one said bolt enclosed by said shell being adapted to receive a said end of one said arm and the other said bolt being adapted to receive a said end of the other said arm in pivotal engagement whereby said other arm may be rotated toward said

arm on said enclosed bolt to be positioned in back to back relationship therewith.

6. In a U-shaped awning frame comprising a front arm having curved ends and opposing side arms extending rearwardly of said front arm from said curved ends, a fixture connecting an end of a said side arm with a said curved end of said front arm, said fixture comprising a rigid shell having a first tubular portion having a longitudinal slot therein and a second U-shaped portion having the open end thereof adjacent said slot, said shell having spaced parallel bolts, one in each said portion and each extending between opposing side walls, one said bolt enclosed by said shell being adapted to receive a said curved end of said front arm in rigid engagement and the other said bolt being adapted to receive a said end of said side arm in pivotal engagement whereby said side arm may be rotated toward said front arm on said enclosed bolt to be positioned in back to back relationship therewith.

7. In a U-shaped awning frame comprising a front arm and opposing side arms having curved forward ends, said arms extending rearwardly of said front arm from opposite ends thereof, a

25

fixture connecting a curved end of a said side arm with a said end of said front arm, said fixture comprising a rigid shell having a first tubular portion having a longitudinal slot therein and a second U-shaped portion having the open end thereof adjacent said slot, said shell having spaced parallel bolts, one in each said portion and each extending between opposing side walls, one said bolt enclosed by said shell being adapted to receive a said end of said front arm and the other said bolt being adapted to receive a curved end of said side arm in pivotal engagement whereby said side arm may be rotated toward said front arm on said enclosed bolt to be positioned in back to back relationship therewith.
